United States Patent Office

HENRY C. SERGEANT, OF COLUMBUS, OHIO.

Letters Patent No. 68,907, dated September 17, 1867.

IMPROVED BRICK MACHINES.

The Schedule referred to in these Letters Patent and making part of the same.

TO ALL WHOM IT MAY CONCERN:

Be it known that I, HENRY C. SERGEANT, of Columbus, in the county of Franklin, in the State of Ohio, have invented a new improvement in Brick Machines; and I do hereby declare that the following is a full and exact description thereof, reference being had to the accompanying drawings, and to the letters of reference marked thereon.

The nature of my improvements consists in the peculiar arrangement of the propeller for shoving the clay into the mould; also, the construction of the track for varying the thickness of the brick, and so arranging the striker-plate or pressure-plate, in connection with an adjustable incline upon the track, that the clay or brick can be pressed harder on one edge to compensate for the friction of the pressure-plate whilst passing out from it, and leave the brick of equal thickness when dry.

To enable others skilled in the art to make and use my invention, I will proceed to describe its construction and operation.

I construct my machine upon the same principle as the old English mould-wheel machine, using the pug-mill, mould-wheel, and gearing of similar construction now in common use in this country.

Figure 1 is a perspective view of the machine.

Figure 2 is a part section of the pug-mill, tub, and its bottom, also the striker-plate, mould-wheel, and the adjustable track.

Figure 3 is a plan view of the track for supporting the followers, also showing the position of the screws for regulating the pressure and the thickness of the brick.

Figures 4 and 5 are plan views of the propeller for filling the moulds.

Letters of reference represent corresponding parts in each figure.

Letters A A, in fig. 1, represent the frame. Letter B represents the tub or hopper for the clay, in which are placed the ordinary mixing-knives, and the shaft D, with the propeller at its lower end. Letter C represents the mould-wheel, which is supported upon a shaft and friction-rollers, and is revolved by the gearing connecting with the shaft D. Letter E represents the projection cast upon the bottom of the pug-mill, to which is fastened the scraper or striker-plate, and made adjustable, as shown in my patent dated June 11, 1867. Letter F represents the wheel and screw for sliding the incline, shown by letter I, backward and forward. Letter G represents the wheel and screw for operating a series of inclines which are placed underneath a section of the track, and having a bearing upon the lower framing. Letter H represents the moulds in the wheel, ten in number. The incline I is constructed of steel, and held to its place by dove-tailed slots and pins, made to travel about two inches. The red lines shown by figures 1 2 3 4 in fig. 4 represent the receiving edges of my propeller, and the form gradually inclines downward to the discharging edges shown by the red lines 1 2 3 4 in fig. 5. The advantage in constructing a propeller of this form can be seen by the line a-b in fig. 4, and by the line a-b in fig. 5. The inside of the cutting edges inclines to a point outward, which increases the friction of the clay to the outside of the tub and prevents the motion of the propeller from turning it around, which prevents filling, and as the clay passes downward near the bottom the form of the propeller is such that it carries the clay into or towards the centre of the pug-mill, as shown by the red lines 1 2 3 4 in fig. 5. Stones that would break the ordinary propeller, by this arrangement are carried to the centre and discharged into the moulds.

Having fully described its construction, I will proceed to describe its operation.

The machine can be driven by horse or steam-power, the power being applied to the shaft D. The tub or hopper being filled with clay, the machine is then put in motion. The clay is tempered by the mixing-knives in the hopper, and is then forced down through the opening in the bottom of the tub into the moulds. The mould-wheel moving in the direction of the arrow, the clay in the moulds is brought out from under the striker-plate and raised to the surface of the mould-wheel by the incline shown at K in fig. 2, where it is taken off. There are many different arrangements for finishing the upper side of the brick made on mould-wheel machines, some using an additional scraper, which leaves the brick thicker on one edge than the other. There is B. M. Gard's patent, June 5, 1866, for extending the striker-plate and pressing directly up against it. The friction is so great that it draws the clay to the back part of the mould, and one side receiving too much pressure, the brick measure one-quarter of an inch larger on one side than the other. I overcome this difficulty by equaliz-

ing the friction on the striker-plate by additional pressure on the counteracting side of the brick. To accomplish this purpose I place an adjustable plate of steel, about one-quarter of an inch thick, upon the track arranged for sliding it backward and forward, and when the moulds get partially covered by the striker-plate the roller on the bottom of the follower rolls up on to the plate and presses one-half or a portion of the clay in the mould, whilst the other portion discharges its surplus out of the remaining opening, as fully shown in fig. 2. This gives the clay in the forward or front side of the mould an increased pressure, and the striker-plate being about the size of the mould, the friction is reduced, so that the brick, when it comes out, has received an even pressure, and will dry both edges the same. By changing the position of the incline or plate, either side can be favored as required. The surplus clay can be discharged under the projection E of the bottom of the pug-mill, back into the tub, or through an outlet to the side of the machine. The bricks can be made of any desired thickness by raising or lowering the section of the track shown at *j j* in fig. 3. This does not alter the pressure, but simply admits more or less clay into the mould. I know that there are patents for adjustable tracks for different purposes, as shown in P. H. Kell's patent, March 26, 1867, for pressing, &c.

I do not claim raising the follower so as to expel the surplus clay whilst under the pug-mill, nor do I claim raising the follower so as to press the brick against the striker or pressure-plate; but what I do claim, is—

1. Raising the follower so as to press a portion of the clay in the mould, and the expelling of the surplus from the mould, in the manner and for the purpose specified.
2. I claim regulating the pressure by means of the sliding-plate, as shown and described.
3. I claim regulating the thickness of the brick by raising or lowering a section of a continuous track by means of wedges and screws, or their equivalents, as shown and described.
4. I claim the construction of a propeller, that the receiving and the discharging edges will operate on the clay as shown and described and for the purpose specified.

HENRY C. SERGEANT.
